UNITED STATES PATENT OFFICE

128,820

DESIGN FOR A COMBINED RADIO AND PHONOGRAPH CABINET

John Huarisa, Chicago, Ill., assignor to Advance
Engineering Company, Chicago, Ill., a part-
nership comprising K. D. Turner, John Huarisa,
L. C. Parks, and J. H. Clippinger

Application April 26, 1941, Serial No. 100,626

Term of patent 14 years

To all whom it may concern:

Be it known that I, John Huarisa, a citizen of the United States, residing in Chicago, in the county of Cook and the State of Illinois, have invented a new, original, and ornamental Design for a Combined Radio and Phonograph Cabinet, of which the following is a specification, reference being had to the accompanying drawings, forming a part thereof.

Fig. 1 is a perspective view of a combined radio and phonograph cabinet showing my new design.

Fig. 2 is a front perspective view showing the doors in the front of the cabinet in an open position.

The other side of the cabinet as viewed in Fig. 1 is substantially the same as the side shown and the back is without embellishment.

I claim:

The ornamental design for a combined radio and phonograph cabinet, as shown and described.

JOHN HUARISA.
